BOTTLE HOLDER ATTACHMENT FOR CHAIRS OR THE LIKE

George E. Schaefer, Muskegon Heights, Mich., assignor to Brunswick Corporation, Chicago, Ill., a corporation of Delaware

Filed Apr. 6, 1960, Ser. No. 60,069

Term of patent 14 years

(Cl. D4—3)

Fig. 1

Fig. 2

Fig. 3

Fig. 2

Fig. 5

Fig. 6

FIG. 1 is a top plan view of a bottle holder attachment for chairs or the like showing my new design;

FIG. 2 is a front elevational view thereof;

FIG. 3 is a right side elevational view thereof;

FIG. 4 is a top plan view of a modified form thereof;

FIG. 5 is a front elevational view of the modified form thereof; and

FIG. 6 is a right side elevational view of the modified form thereof.

The sides opposite those shown in FIGS. 3 and 6 are substantially the same in appearance as those disclosed.

The back not shown is substantially plain.

I claim:

The ornamental design for a bottle holder attachment for chairs or the like, substantially as shown and described.
